UNITED STATES PATENT OFFICE.

EMORY O. ONION, OF SUMMUM, AND CHARLES D. SNIVELY, OF IPAVA, ILLINOIS.

FRACTURE AND EXTENSION APPARATUS.

1,108,469.

Specification of Letters Patent. Patented Aug. 25, 1914.

Application filed July 27, 1910. Serial No. 574,031.

To all whom it may concern:

Be it known that we, EMORY O. ONION and CHARLES D. SNIVELY, citizens of the United States, residing, respectively, at 5 Summum and Ipava, in the county of Fulton and State of Illinois, have invented certain new and useful Improvements in Fracture and Extension Apparatuses, of which the following is a description, reference being had to the accompanying drawing, which forms a part of our specification.

The object of our invention is to provide a device which is more especially applicable for use in connection with fractures of 15 limbs, or curvature of the spine and similar difficulties; the object being to provide an apparatus into which the fractured limb or portion of the body may be placed, to not only act as a support, but also enable tension to be applied so that the contracted muscles may be thoroughly expanded and, in the case of a fracture, permit the fractured bone to be properly set and maintained in such condition.

25 The apparatus may also be applied to other uses, possessing a number of advantages that will be apparent from the construction shown in the drawing and described in detail in the following specification.

30 In the drawing:—Figure 1 is a plan view of our improved apparatus with the right hand portion thereof being shown partially in section. Fig. 2 is a view taken on the 35 line 2—2 of Fig. 1 looking toward the left of said figure. Fig. 3 is a detail view of a modified form; while Fig. 4 is a cross-sectional view of Fig. 3, to more clearly show the relation of the mechanism whereby the 40 device may be expanded.

The apparatus is preferably so formed 45 that it may be readily applied to or fitted about a limb or body; the side pieces being preferably made substantially straight, while the ends are bowed to conform with the curvature of limb or body, thus forming what may be termed a cradle in which the limb or portion to be treated rests.

50 The apparatus is preferably made of metal or other suitable material possessing the requisite rigidity, and comprising the two portions of members *a* and *b* bent into U-shape, with the middle portion of the U preferably bent somewhat at an angle to the side portions for the purpose previously stated. One of the members, to wit, member

a, is preferably hollow in the nature of tubing to receive the side or end portions of the member *b*, as clearly shown in Fig. 1. We prefer to have the inside diameter of the legs or side portions of member *a* slightly larger than the diameter of the side portion or legs of the member *b* so as to provide a slight play between the members and thereby enable one side or leg of member *b* to be 60 extended somewhat beyond the other without causing the parts to bind. The legs or side portions of the member *b* are screw threaded as indicated at *c* to receive the nuts *d* which take against the ends of member *a* as shown in Figs. 1 and 2. These nuts *d* control the relation between the two members *a* and *b* as is readily apparent from the construction shown; by turning the nuts *d*, in one direction, it is evident that 65 they will force the member *b* outward and thereby extend the apparatus. With the nuts or members *d* taking against the ends of the member *a* they will prevent the telescoping of said members.

70 The member *a* is provided with the two rings *e*, *e* or other suitable mechanism, preferably secured at diametrically opposite points near the point where the member *a* is bowed. Member *b* is also provided with 75 similar mechanism or rings *f*, *f*, also located at diametrically opposite points: the rings being preferably so arranged that the distance between the rings *e* and *f* on both sides of the apparatus will normally be 80 spaced the same distance apart.

85 When it is desired to use our improved apparatus, for example, in connection with a fractured arm, the arm is first provided with bandages or "boots" to opposite sides 90 of the fracture; the arm is then placed in the apparatus with the bowed portions of the members beneath the arm; straps or cords are then secured through the rings *f*, *f* to the adjacent "boot" or bandage, while 100 straps or cords are also passed through the rings *e*, *e*, and secured to the adjacent "boot" or bandage which has been placed to the opposite side of the fracture. The nuts or means *d*, *d* are then turned in a direction so 105 as to force the members *a* and *b* in opposite directions causing the apparatus to be expanded. With the "boots" or bandages secured to their respective set of rings, it is 110 apparent that the arm or limb and its muscles will be put under tension; and the nuts are turned until the muscles have been

drawn or stretched sufficiently to permit of the setting of the fractured bone; the apparatus being left in place and in its extended condition until the fracture is sufficiently healed, or bandaged.

If for any reason it is desired to obtain a greater amount of tension on one side than on the other, the fact that the inside diameter of member *a* is somewhat larger than 10 the diameter of member *b*, will permit of the means, on the side the greater tension is required, being turned until that side of the apparatus is more extended than the other.

It is apparent from the description just 15 given that our apparatus may be applied to other uses, as for instance in connection with a curvature of the spine, where it will be desired to have a greater amount of tension on one side than on the other. Furthermore, 20 our construction permits of an increasing or diminishing amount of tension being applied from time to time as the nature or condition of the case requires.

In Fig. 3 we have shown a modification 25 wherein the member *a* is provided with a worm wheel *g* which is suitably secured to both legs of the member *a* by the housing *h*. The sides or legs of the member *a* are cut away at a point adjacent the worm wheel *g* 30 so as to permit the wheel to extend into the member *a* and mesh with the teeth with which the ends or legs of member *b* are provided. With this construction it is of course only necessary to have the teeth or threads 35 formed on one side of the legs or member *b* as clearly shown in Fig. 3, thus providing

what may be termed a rack and pinion construction. It is apparent from this construction that the operating means will not only force the telescopic members apart, 40 that is, expand the device, but will also lock or maintain the members in their adjusted positions.

We have illustrated and described the simplest forms of our invention, but it is 45 readily apparent that these constructions may be altered in a number of details without departing from the spirit of our invention, and we do not wish, therefore, to be understood as limiting ourselves to the exact 50 construction shown and described, but

What we claim as our invention and wish to secure by Letters Patent is:—

A device of the class described, comprising 55 a pair of substantially U-shape telescopic members, the ends or legs of the inner member being screw threaded, the portions of both members intermediate of their ends being bowed at an angle to the axes of said ends, rotative members operatively connected with the ends of both members, but maintained against movement lengthwise of the outer member, whereby the relation of both ends or legs may be independently controlled, and attaching means secured intermediate of the ends of both members. 60 65

EMORY O. ONION.
CHARLES D. SNIVELY.
